UNITED STATES PATENT OFFICE.

JEFFERSON CAYLOR, OF INDIANAPOLIS, INDIANA, ASSIGNOR TO GENERAL BOX COMPANY, OF CHICAGO, ILLINOIS, A CORPORATION OF DELAWARE.

BOX.

Application filed June 30, 1923. Serial No. 648,735.

This invention relates to boxes, and more particularly to wirebound and similar boxes.

Among other objects, the invention aims 5 to provide a box of light and strong construction, which may be repeatedly used for shipping purposes without unfastening its bindings.

Other objects will appear as the description proceeds.

An illustrative box containing an embodiment of the invention is shown in the attached drawing, in which:

Fig. 1 is an elevation showing the box blank and a head in position for assembling,

Fig. 2 is a plan view looking down upon the top of the completed box.

Fig. 3 is a perspective view of the completed box showing its detachable cover in closing position,

Fig. 4 is a transverse sectional view through the top of the box particularly showing the structure and relationship of 25 the parts of the detachable head, taken on the line 4—4 of Fig. 2,

Fig. 5 is a perspective view of the two parts of the detachable head for the box,

Fig. 6 is a perspective view of the upper 30 end of the box showing one of the parts of the detachable head about to be placed in position relative to the cleats in the head,

Fig. 7 is a perspective view of the bottom 35 head of the box, and

Fig. 8 is a perspective view of the bottom of the box showing the head illustrated in Fig. 7, in position relative to the cleats of the box.

The body of the illustrative box is formed 40 from a wirebound cleated blank shown in Fig. 1. When the blank is folded into box form, and the continuity of its binding wires is completed by tying or fastening

45 their extremities, the cleats of the respective sections of the blank cooperate in the usual manner to form approximately rigid cleat frames at the opposite ends of the box, spaced apart and held by the side material and bound by the wire bindings and 50 resisting the tension of said bindings, as well understood in the art.

A hexagonal form of box is illustrated, and the foldable blank accordingly com-

prises six sections 1, 2, 3, 4, 5 and 6. These 55 sections consist of suitable side material, such for example as wood veneer, attached to end cleats 7, 8, 9, 10, 11 and 12 respectively, and the several sections including the cleats are connected in cooperative fold- 60 able relationship by the binding wires 13, certain of which are stapled through the side materials to the cleats.

The blank may be folded into box form around one head, herein shown as a unitary 65 sheet metal structure 14 (Figs. 1, 7 and 8). This head 14 forms the bottom or closed end of an openable box, the other end or top of which may be closed, after filling or packing of contents, by the insertion of 70 the detachable cover 15 (Figs. 2 to 6).

The sheet metal head 14 for the bottom or lower end of the box is shown having flanges struck up from its marginal portions, as indicated by the numerals 29, 30, 75 31, 32, 33 and 34 in Fig. 7 of the drawings. These flanges are adapted to extend into the lower cleat frame in such a manner that each flange shall be contiguous to a corresponding cleat. They serve to provide angle reinforcement and also as attaching flanges by which the head may be conveniently attached to all of the cleats of the lower end of the box by fastenings driven externally of the box through said flanges. 85 The margins of the head bear against the inner faces of the cleats, thus cooperating with the fastened flanges in holding the head in place against the thrust of the contents of the box.

If desired, the cleats of the lower end of the box may be attached to the head 14 both by fastenings driven from inside the box through the margins of the head and by fastenings driven outside the box 95 through the said attaching flanges; thereby further strengthening and rigidifying the box.

It will be observed that the oppositely arranged flanges 29 and 32 (Figs. 7 and 8) 100 are sufficiently long to provide angle reinforcement along the major portions of the lengths of two opposite cleats, and the portion of the head formed with these flanges provides in effect a brace or strut across the 105 head.

For further stiffening and strengthening effect, the head 14 may be suitably corru-

gated or provided with stamped ribs. One appropriate form of corrugated head for a box of the illustrative type is shown, providing concentric ribs 35 consisting of portions of the head stamped so as to project outwardly with respect to the center of the box.

After the box is filled or packed with contents for shipment, its open upper cleat frame may be closed by a cover which is insertable through the upper cleat frame, such a cover being herein shown as composed of complementary sheet metal sections 17 and 18 (Figs. 5 and 6). These sections are shown formed with marginal flanges designated in Figs. 4, 5 and 6 by the numerals 21 to 28 inclusive, these flanges being arranged relative to the cleats in the same general manner as are the flanges of the bottom head 14.

The complementary sections of the insertable cover are constructed with cooperating formations, herein shown as interlocking ribs 19 and 20, which may be conveniently constructed by striking up portions of the sections in a stamping operation. When these ribs are interlocked as shown in Figs. 3 and 4, they act to cause the sections to function practically as a unitary head.

The section 17 is constructed with a pair of parallel upwardly extending flanges 25 and 28, which permit it to be inserted in the upper cleat frame between the parallel cleats 7 and 10. After this insertion, the section 17 is moved to the left (Fig. 6) so that its marginal portions lying between the flanges 25, 26, 27 and 28 become positioned underneath the cleats 8 and 9. The ribbed portion 19 is then depressed until the section lies in a plane parallel with the plane of the cleat frame and the tops of the flanges 25 and 28 are positioned in or below the upper plane of the frame. The flanges 25, 26, 27 and 28 may then be secured to the adjoining cleats 7, 8, 9 and 10, by nails, screws or other appropriate fastenings.

When the above described steps have been completed, the complementary section 18 is similarly inserted in the upper cleat frame and pushed to the right, as indicated in Fig. 6, to bring its marginal portions under the cleats 11 and 12. As shown in Fig. 6, the section 18 during its insertion slides over the rib 19 until its flanges 21, 22, 23 and 24 are positioned against the cleats 7, 10, 11 and 12. Said section 18 is then depressed until the rib 20 interlocks with the rib 19, as indicated in Fig. 4, preventing the flanges from moving out of contact with the cleats, and forming a transverse strut extending between and abutting against opposite cleats of the upper cleat frame. The several flanges of the section 18 may then be secured to the respective cleats 7, 10, 11 and 12 by appropriate fastenings.

The illustrative box constitutes a practicable and reliable shipping medium, capable of extraordinary resistance to distortive strains but possessing sufficient flexibility to yield without breakage when subjected to rough usage; and by reason of the provision of the readily detachable cover may be repeatedly used for shipment without impairment of its integrity by disruption or unfastening of the binding wires.

When the box is filled and closed, as above described, it has all of its cleated sections firmly tied together by the binding wires and by the head sections themselves, and the opposite heads secured to all of the cleated sections, which contributes to the strength and rigidity of the package and prevents bowing or separation of the box sides or unsecured margins with accompanying exposure or bulging of contents.

The heads of the box, being of material such for instance as thin sheet iron or other thin sheet metal of appropriate stiffness, contribute an element of elasticity to the box and cooperate with the wire bindings in flexibly resisting distortive strains and in tending to restore the box to original shape after release from such strains. For instance, if the box should be dropped upon a trihedral corner or otherwise subjected to diagonal strain, the cleated sections of the box may flex or shift slightly relatively to one another, with accompanying flexure of the binding wires and flexing of the metal heads of the box; while the tensioning of the binding wires and the stressing of the heads will cooperate in resisting such movements and in restoring the box to its original form after the strain is released. The structure of the heads is such as to offer considerable bracing and to increase materially the resistance to flexing, as well as to prevent inward bowing of the heads.

Heads of material such as thin sheet metal also combine the advantages of lightness with adequate stiffness, non-frangibility and capacity of bending under such severe strains as would disrupt ordinary wooden headed boxes.

Boxes of the above described construction may be manufactured with somewhat smaller dimensions than like boxes constructed with wooden heads, without sacrificing the capacity of the box. By virtue of the thin material employed for the heads, boxes of specified interior dimensions may be made with shorter sections of material for the foldable cleated sides of the box. This importantly contributes to lightness of construction and also results in an appreciable saving of material in the manufacture of such boxes on a large commercial scale, and an appreciable gain of space in the storage of such boxes in large quantities. Furthermore such boxes possess unusual strength

and rigidity, combined with a desirable elastic property, promoting the capability of the box to successfully endure rough usage.

It will be obvious that the present invention is not limited to the specific details of construction of the illustrative box, since such details may be variously modified to suit the different forms and dimensions of wirebound boxes required for different shipping purposes.

Claims covering the illustrative structure are made in applications for sheet metal headed wirebound boxes filed by the present inventor June 2, 1923, and June 30, 1923, Ser. No. 643,010 and Ser. No. 648,733 respectively.

Having described an embodiment of my invention, I claim:—

1. A box of the class described comprising, in combination, cleat frames; side material for successive box sides enclosing and secured to said cleat frames; binding means around said side material and cleat frames; and sheet metal heads having margins abutting the inner sides of said cleat frames and flanges lapping and secured to cleats thereof; said head being constructed to permit insertion and removal after the box is filled.

2. A box of the class described comprising, in combination, cleat frames each consisting of more than four angularly-related cleats having abutting ends; side material enclosing and secured to said cleat frames; metallic bindings around said side material and cleat frames; and sheet metal heads respectively secured to all of the cleats of the respective cleat frames, said heads having attaching flanges struck up from their margins adjacent the inner faces of the corresponding cleats.

3. A box of the class described comprising, in combination, cleat frames each consisting of more than four angularly-related cleats having abutting ends; side material enclosing and secured to said cleat frames; metallic bindings around said side material and cleat frames; and sheet metal heads respectively secured to all of the cleats of the respective cleat frames, one of said heads comprising interlocking parts insertable and removable from the end of the box.

4. A wirebound box comprising, in combination, a foldable wirebound blank having cleats cooperable to form cleat frames at the ends of the box; and thin heads of

stiff, bendable material constructed and adapted to be secured respectively to each of the cleats of the respective cleat frames, one of the heads being constructed of complementary members having interlocking ribs so as to be readily placed in position within a cleat frame after the box is packed.

5. A wirebound box comprising, in combination, a foldable wirebound blank having cleats cooperable to form cleat frames; and thin heads of stiff, bendable material constructed and adapted to be secured respectively to each of the cleats of the respective cleat frames; one of said heads being constructed of a plurality of interlocked parts so as to be readily secured in position between the cleats of a cleat frame after the box is packed.

6. A wirebound box comprising, in combination, a foldable wirebound blank having mating cleats cooperable to form cleat frames; and heads constructed and adapted to be secured respectively to each of the cleats of the respective cleat frames, one of said heads forming a detachable top for the box and being constructed of interlocked complementary parts each insertable in proper position with its margins beneath the top cleat frame after the box has been packed.

7. A wirebound box comprising, in combination, cleat frames; side material for successive box sides enclosing and secured to said cleat frames; binding means around said side material and cleat frames; and a detachable box head removably secured in one of said cleat frames; said box head comprising complementary sheet metal parts, the margins of which are insertable under said cleat frame, said parts having struck up attaching flanges abutting interior faces of cleats of said cleat frame.

8. A box of the class described comprising, in combination, cleat frames; side material for successive box sides enclosing and secured to said cleat frames; wire bindings around the box; sheet metal heads secured in one of said cleat frames having concentric annular corrugations; and a sheet metal head secured to the other cleat frame composed of parts united diametrically of the head by interlocking ribs to provide a transverse brace or strut.

In testimony whereof, I have signed my name to this specification.

JEFFERSON CAYLOR.
